UNITED STATES PATENT OFFICE.

DANIEL EDWARD QUICK, OF TAFT, CALIFORNIA.

SEPARATOR.

Application filed December 16, 1925. Serial No. 75,791.

This invention relates to separators and it has for its object to provide an improved device of this character adapted to separate a liquid from a gas, or one liquid from another, in a quick and efficient manner. The invention is designed, primarily, to separate water from gas in gas mains or to separate water from oil in oil mains, automatically and continuously.

One of the principal objects of the invention is to provide a separator, of the character indicated, which will be extremely accurate and sensitive in action.

With these objects in view, I have devised the structure shown in the accompanying drawing, wherein:

Fig. 1 is a longitudinal, vertical sectional view of a separator constructed in accordance with the invention,

Fig. 2 is a plan view of a sliding joint, hereinafter described,

Fig. 3 is a transverse, vertical section through one of the fans by which the valve operating mechanism is mounted in the main casing, and

Fig. 4 is a plan view of a valve stem, hereinafter described.

Like numerals designate corresponding parts in all of the figures of the drawing.

Referring to the drawing, the numerals 1 designate caps which close the ends of a main tubular casing 2. A sleeve 3, which projects downwardly from the lower part of the casing 2, near one end thereof, carries a valve nipple 4, which nipple has a relatively small drip port 6 formed therein. The port 6 is adapted to be closed by a valve 7. It is to be noted that the valve seat is not concave, but is flat on top. This in conjunction with the half round form of the valve provides a structure that will be very sensitive and will unseat easily; because it will not stick. It is also to be noted that the sleeve 3 is projected into casing 2 so that coarse particles and sediment will be trapped in the casing instead of passing out through the valve. This eliminates a great deal of wear on the valve and seat. A spider 8, which is carried by the valve stem 9, spans the nipple 4 and acts as a guide for the valve as it moves up and down in said nipple. The upper end of the valve stem 9 is provided with a series of openings 10. A cotter pin or key 11 is adapted to be passed through any one of these openings and through the head 12 of valve operating rod

5. The rod 5 is threaded for the reception of nuts 13, which lie upon opposite sides of a transversely extending bar 14, said nuts serving to bind bar 14 and rod 5 rigidly together. The outer ends of the bar 14 are trunnioned in a band 17, said band being held in place in the casing 2 by means of screws 15. Longitudinally extending strips 16 connect the band 17 to a corresponding band 17^a. Valve operating rod 5^a is trunnioned with respect to the band 17^a, by elements 13 and 14, which correspond with the like elements by which the rod 5 is pivoted with respect to the band 17. The confronting ends of the rods 5, 5^a are connected by means of a pivoted and sliding joint. This joint consists of a male member 23, which is secured to the rod 5 by bolt 21 and a female member 24 which is secured to the rod 5^a by bolt 21^a. A pivot bolt 22 passes through the slotted portion 20 of the members 23 and 24 and, in effect, pivotally unites these members while permitting them to have limited endwise adjustment. The free end of the rod 5^a carries a float 20^a, secured upon the outer end of said rod 5^a by means of a nut 19. The float 20^a is provided with a cover 18 and is fluid tight. The inlet for the materials to be separated is indicated at 25, while the outlet for the materials separated, such, for example, as the water separated from a body of oil, is through port 6. The inlet and outlet may be placed at any desired point, the location being a matter of choice. However the location of the outlet at the top of the casing will prevent accumulation of gas therein, which is desirable. If desired, an outlet 26 may be provided so that oil or gas may flow continuously through casing 2 from inlet 25 to outlet 26, the separated material such as water, in either case, passing off through port 6. It will be observed that the structure provided is one which will be extremely sensitive in operation and one which will be capable of very accurate adjustment. Very minute adjustment may be effected by the longitudinal movement of the rods 5, 5^a, under the influence of the nuts 13. It is to be noted that the connection between rods 5, 5^a is in the nature of a toggle joint and that the fulcrums are arranged so that the float acts with considerable leverage in seating the valve.

It is to be understood that the invention is not limited to the precise construction set

forth but that it includes within its purview whatever changes fairly come within either the terms or the spirit of the appended claims.

5 Having described my invention, what I claim is:

1. A device of the character described comprising a casing having an outlet port, a valve for controlling said outlet port having a stem, a float, a pivoted rod by which said float is carried, a pivoted rod connected to the valve stem, a pivotal connection between the abutting ends of the said rods, and means for effecting individual endwise adjustment of said rods with respect to their pivot points.

2. A device of the character described comprising a casing having an outlet port, a valve for controlling said outlet port having a stem, a float, a horizontally disposed rod by which said float is carried, means for pivoting said rod intermediate its ends, a second horizontally disposed rod pivoted intermediate its ends and connected at one end to the valve stem, the said rods being disposed in substantial longitudinal alignment with each other and having sliding and pivotal connection at their abutting ends.

3. A device of the character described comprising a cylindrical casing, a pair of spaced rings fitted within the casing, spacing elements extending between said rings, means for securing one of said rings to the casing, a transverse trunnion extending diametrically of each of said rings, a pair of rods disposed end to end and having pivotal connection with each other at their abutting ends, said rods being pivotally mounted intermediate their ends upon the said trunnions, a float carried by the outer end of one of said rods, a valve supported from the outer end of the other of said rods, and an outlet port leading from the casing and controlled by said valve.

4. A device of the character described comprising a casing, having an outlet port, a vertically disposed valve and valve stem controlling said port, a float, a horizontally disposed rod by which the float is carried,

means for pivotally mounting said rod intermediate its ends, means for effecting endwise adjustment of said rod with respect to its pivot point, a second rod, means for pivotally connecting one end of the second rod to the valve stem and the other end of the second rod to that end of the first rod remote from the float, and means for effecting longitudinal adjustment of the second rod with respect to its pivot point.

5. A structure as recited in claim 5, wherein the connection between the confronting ends of the said two rods is a sliding one.

6. A device of the character described, comprising a casing having an outlet port, a vertically disposed valve and stem controlling said port, a float in the casing, a pair of horizontally disposed rods, said float being mounted upon the outer end of one of said rods, said rod being pivoted intermediate its ends, means for pivotally connecting the end of the other of said rods to the valve stem, means for pivoting the second rod intermediate its ends and means for uniting the confronting ends of said two rods, comprising male and female slotted members, and a bolt traversing said members.

7. A device of the character described comprising a casing, a sleeve the upper end of which is projected above the bottom of and into said casing, an element at the lower end of the sleeve constituting an outlet port, a valve and stem vertically movable in the sleeve said valve co-acting with said outlet port, a float in the casing, a pair of horizontally disposed rods said float being mounted upon the outer end of one of said rods and said rod being pivoted intermediate its ends, means for pivotally connecting the other of said rods to the valve stem, means for pivoting the second rod intermediate its ends and means for pivotally uniting the confronting ends of said two rods.

In testimony whereof he affixes his signature.

DANIEL EDWARD QUICK.
